UNITED STATES PATENT OFFICE

DEAN S. BARNARD, OF HINSDALE, ILLINOIS, ASSIGNOR TO THE ROME COMPANY, INC.,
A CORPORATION OF NEW YORK

MEANS TO SECURE COILED SPRINGS TO A SUPPORT

Application filed June 15, 1931. Serial No. 544,490.

In spring cushions of the coiled bed spring type, for example, it is customary to support the springs from below on cross bars of a spring frame. Usually, in all metal structures, the springs are secured to the bars by screwing them into interlocking engagement with heavy wires extending transversely of the bars in about the plane of the tops thereof and looped under the same. It is evident that the springs, fastened in this way, are not securely held. Furthermore, there are a great many springs in a bed spring, and the labor involved in properly mounting them is, therefore, considerable.

The object of the present invention is to produce a simple and novel fastening between a spring and a bar that will eliminate the screwing of the same into position, greatly reduce the amount of labor involved in mounting the springs, and insure that the springs will be positively locked to their supporting bars.

In carrying out my invention I employ a simple fastening device which is slipped on the supporting bar and then into the end of the spring, the portion that enters the spring being then deformed to press the end of the spring against the bar and hold it there. In the actual manufacture of spring cushions the deformation of all of the fastening devices may be performed at one time by suitable mechanism, so that the time and manual effort involved in making the assembly is only that required to set a frame on the ends of the entire group of springs, and lay across the frame wires provided with the fastenings; whereupon it is but the work of a moment to secure all of the fastenings.

The various features of novelty whereby my invention is characterized will hereinafter be pointed out with particularity in the claim; but, for a full understanding of my invention and of its objects and advantages, reference may be had to the following detailed description taken in connection with the accompanying drawing, wherein:

Figure 1 is a more or less diagrammatic plan view of a metal bed spring to which my invention is applied, only a portion of the springs being shown; Fig. 2 is an elevation

of one of the vertical coiled springs, the supporting bar therefor being in section, and the fastening between the spring and bar being shown in elevation; Fig. 3 is a section, on a larger scale, on line 3—3 of Fig. 2; Fig. 4 is a side view of that portion of the supporting bar underlying the spring in Figs. 2 and 3; Fig. 5 is a fragment of one of the wires having the fastenings, on a larger scale than Fig. 2 and on a smaller scale than Fig. 3, and prior to deforming the fastening; and Fig. 6 is a top plan view of the fastening as it appears in Fig. 5.

In the drawing I have illustrated a well known type of bed spring in which there are many vertical coiled springs 1 arranged in transverse and longitudinal rows, the springs of each transverse row resting on cross bars 2 of which there are as many as there are springs in each longitudinal row. These bars are usually flat strips of rectangular section set on edge, although they may take any desired shape.

In accordance with my invention, the springs rest on the cross bars and are firmly held thereto by simple fastenings or ties applied while the springs and bars remain stationary. Each bar is preferably notched in the top, as indicated at 3, 3, to provide seats for the lowermost coil of each spring resting thereon. The fastenings are simple members slipped upon the bars from below and into the lower ends of the springs, after which they are deformed to lock the springs in place. Considering only a single fastening, it may conveniently be made of a piece of heavy wire bent into the shape of a U whose arms are spaced apart a distance about equal to the internal diameter of the lowermost coil of one of the coiled springs; the yoke portion of the U being fashioned into a depending, long, narrow U the spacing between the arms of which is about equal to the thickness of one of the bars so as to permit a bar to be received between the arms. After this device is slipped up on a bar and into an overlying spring, the free ends of the arms are bent out over one of the lower coils, drawing the end of the spring and the bar together.

Preferably, the fastenings are made in

gangs each sufficient to secure all of the springs in a single longitudinal row; and that is the form illustrated.

In the arrangement shown, there is a series of heavy longitudinal wires 4, one wire for each longitudinal row of springs. At the proper points each wire is bent, as shown in Figs. 5 and 6, to form therein U-shaped elements each having double arms 5 and 6 10 and a connecting piece or yoke 7 formed of a single wire. The part 7 is bent to produce a depending narrow U-shaped element 8.

The bed spring, completed except to fasten the springs to the under frame, is laid upside down, the under frame is set on the springs, and the wires 4 are laid across the bars. The bars are embraced by the element 8, and the double arms 5 and 6 extend up into the springs, engaging with the inner 20 sides of the lower coils and thus centering the springs. The bars are preferably notched on the under side, as indicated at 9, to form seats for the elements 8 of the fastenings. The free ends of the arms 5 and 25 6 are then bent outwardly between the coils of the springs, pressing those coils lying between them and the bars firmly against the bars, as shown in Figs. 2 and 3. After the fastening of the springs has been completed, 30 the springs are positively held against movement relatively to the bars; both the fastening devices and the springs being interlocked with the bars against movement along the latter; the fastenings being interlocked with 35 the bars against transverse movement relatively thereto; the fastenings serving as centering posts for the springs to prevent movements of the springs transversely of the bars; and the fastenings, springs and bars being 40 united and interlocked against relative vertical movements.

It will thus be seen that my improved fastenings are not only simple but extremely efficient, so that I am able to obtain a better 45 spring structure at a lower cost than has been possible under the old practices.

While I have illustrated and described with particularity only a single preferred form of my invention, I do not desire to be limited to the exact structural details thus illustrated and described; but intend to cover all forms and arrangements which come within the definitions of my invention constituting the appended claim.

55 I claim:

In a spring cushion, a series of parallel bars, vertical coiled springs arranged in a row one upon each bar, a heavy wire extending transversely to the bars underneath the 60 springs, said wire having at each bar a bend in the form of a U provided with a central depending narrower U, each narrower U embracing the corresponding bar from the side opposite that on which the spring is located, each wider U fitting into the end of the ad-

jacent spring, the arms of each wide U being composed of two sections of wire lying side by side in a plane parallel with the length of the corresponding bar, and the ends of the arms of each wide U being bent outwardly over a coil of the spring within which it lies to hold the spring against the underlying bar.

In testimony whereof, I sign this specification.

DEAN S. BARNARD.
